US00D901481S

(12) United States Design Patent (10) Patent No.: US D901,481 S
Ahn (45) Date of Patent: * Nov. 10, 2020

(54) CASE FOR ELECTRONIC COMMUNICATIONS DEVICE

(71) Applicant: SPIGEN KOREA CO., LTD., Seoul (KR)

(72) Inventor: Deok Hyun Ahn, Seoul (KR)

(73) Assignee: Spigen Korea CO., LTD., Seoul (KR)

() Term: 15 Years

(21) Appl. No.: 29/703,476

(22) Filed: Aug. 27, 2019

(51) LOC (12) Cl. 14-03

(52) U.S. Cl.

USPC D14/250

(58) Field of Classification Search

USPC ..... D3/201, 218, 226, 227, 247, 249, 250, D3/269, 303; D13/103, 107, 108, 119; D14/137, 138 R, 138 AA, 138 C, 138 G, D14/172, 192, 203.3–203.7, 217, 238.1, D14/247, 248, 250–253, 434, 440, 447, D14/496

(57) CLAIM

The ornamental design for a case for electronic communications device, as shown and described.

DESCRIPTION

FIG. 1 is a front perspective view of a case for electronic communications device showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

1 Claim, 8 Drawing Sheets
